UNITED STATES PATENT OFFICE

WALTER PARKS GRAY, OF CINCINNATI, OHIO, ASSIGNOR TO THE CROSLEY RADIO CORPORATION, OF CINCINNATI, OHIO, A CORPORATION OF OHIO

DESIGN FOR A RADIOCABINET

Application filed August 1, 1930. Serial No. 36,530. Term of patent 3½ years.

To all whom it may concern:

Be it known that I, WALTER PARKS GRAY, a citizen of the United States, and a resident of Cincinnati, in the county of Hamilton and State of Ohio, have invented a new, original, and ornamental Design for a Radiocabinet, of which the following is a specification, reference being had to the accompanying drawing, forming part thereof.

In the drawing:

The figure is a perspective view of the design.

I claim:

The ornamental design for a radio cabinet, as shown.

WALTER PARKS GRAY.
